UNITED STATES PATENT OFFICE.

ALBERT D. LESSER, OF NEW YORK, N. Y.

CAP.

Application filed March 3, 1927. Serial No. 172,245.

This invention relates to headwear such as caps and has as an object to provide a cap having a series of small receptacles formed therein for the purpose of carrying conveniently, and in a manner to provide ready access, articles such as golf tees which it is desired to remove and replace from time to time.

Other objects and advantages of the invention will appear hereinafter.

A preferred embodiment of the invention selected for purposes of illustration is shown in the accompanying drawings, in which, Figure 1 is a perspective view of a cap. Figure 2 is an enlarged detail view, and Figure 3 is a section through one of the receptacles.

According to the invention, it is proposed to secure to the cap a strip of material, preferably of the same character as that forming the body of the cap. The said strip is preferably secured to the cap along three edges, the fourth edge being free. The said strip is also preferably stitched to the body of the cap along a plurality of spaced parallel lines which form individual receptacles for the articles.

Referring to the drawings, the preferred embodiment of the invention has been illustrated as applied to a cap of usual design consisting of a series of substantially V-shaped pieces of fabric 1 which are stitched together along the seams 2. In such caps, the free edges of the pieces 2 are usually stitched to the sweat-band 3 inside the cap. In order to form the receptacles for the articles to be carried, a strip of fabric 4, preferably of the same material as the body of the cap, is secured along the bottom edge thereof adjacent the sweat-band, the vertical edges 5 and 5' of the strip 4 being secured within the adjacent seams 2 while the bot-

tom horizontal edge 6 of the strip is secured with the bottom edge of the V-shaped piece to the sweat-band. The upper free edge of 45 the strip is folded over and hemmed along the line 7, and in order to provide individual receptacles of a size and type adapted for holding articles such as golf tees, the strip is stitched to the body of the cap along a 50 plurality of lines 8, thus forming a plurality of individual receptacles 9.

When in use, the receptacles may be filled with a plurality of golf tees which may readily be removed from or inserted in the cap 55 without involving the necessity of removing the cap from the wearer's head.

It will be understood that the invention may be variously modified and embodied within the scope of the subjoined claims. 60

I claim as my invention:

1. A cap having a strip of material having two of its edges stitched to the body of the cap and having a third edge turned under the edge of the body of the cap and secured 65 to the sweat-band, between said sweat band and the body of the cap, said strip being fastened by rows of transverse stitching to the body of the cap to form a series of compartments. 70

2. A cap provided with vertical seams near the edge, said cap having a strip of material two edges of which are secured in the seams thereof and having a third edge turned under the edge of the body of the cap 75 and secured to the sweat band, between said sweat band and the body of the cap, said strip being fastened by rows of transverse stitching to the body of the cap to form a series of compartments. 80

In testimony whereof, I have signed my name to this specification this 1st day of March, 1927.

ALBERT D. LESSER.
